UNITED STATES PATENT OFFICE.

THOMAS I. DUFFY, OF CHICAGO, ILLINOIS, ASSIGNOR TO HENRY ELLSWORTH AND ALBERT E. CROSS, COPARTNERS, AS FIRM OF ELLSWORTH & CROSS, OF CHICAGO, ILLINOIS.

DEMOUNTABLE WHEEL.

1,099,169.

Specification of Letters Patent.

Patented June 9, 1914.

Application filed January 16, 1911. Serial No. 602,797.

To all whom it may concern:

Be it known that I, THOMAS I. DUFFY, a citizen of the United States, and a resident of Chicago, in the county of Cook and 5 State of Illinois, have invented certain new and useful Improvements in Demountable Wheels; and I do hereby declare that the following is a full, clear, and exact description thereof, reference being had to the accompanying drawings, and to the characters of 10 reference marked thereon, which form a part of this specification.

This invention relates to improvements in hubs for demountable wheels, more especially 15 adapted for automobile uses, of that type shown in my prior application for United States Letters Patent, filed May 2nd, 1910, Serial Number 568,807.

The present invention relates to novel 20 means of constructing and arranging the locking device by which the inner and outer hub members or shells are forced and locked together, and relates also to improved means for locking the assembled hub members from 25 relative rotation.

The invention consists in the matters hereinafter set forth and more particularly pointed out in the appended claims.

In the drawings,—Figure 1 is an axial section 30 of a demountable wheel hub embodying my invention, showing fragments of the spokes. Fig. 2 is an inner end elevation of the assembled hub shown in Fig. 1. Fig. 3 is a partial inner end elevation of the outer shell or hub member. Fig. 4 is a like view of 35 the inner hub member or shell. Fig. 5 is a fragmentary detail of the outer end of the locking ring by which the hub members are locked together, showing a novel form of wrench engaging lugs by which to turn the ring. Fig. 6 is a plan view of the part shown 40 in Fig. 5. Fig. 7 is an axial section of a rear hub embodying my invention, showing a brake drum applied thereto. Fig. 8 is an inner end elevation of the hub shown in Fig. 7.

First referring to the hub shown in Figs. 1 to 6, inclusive, which may constitute the hub of the front wheel of an automobile, said hub comprises as its principal elements an inner shell or member 10 which is interiorly fashioned to receive the anti-friction bearings of the hub, (not shown) and an outer shell or member 11 which is fitted over the inner member and is arranged to carry the rim, spokes and tire of the wheel. The outer hub

member is provided at its inner end with an integral flange 12, and is provided at its outer end with a flange 13 which is removably fitted over said outer member, and between which and the flange 12 the spokes 14 60 of the wheel are confined; said flanges being clamped upon the interposed spokes by the bolts 15. The inner hub member 10 is formed at its rear end with an exterior taper or cone-like surface, said member being made 65 largest at its inner end, and the outer shell or member 11 is formed with an interior taper or cone-like surface complementary to and adapted to interfit with the exterior taper of said inner member. The said inner member is elongated beyond the outer member 70 to provide a space to receive the end of the axle and the anti-friction bearings therefor, and is exteriorly screw-threaded at its outer end to receive a dust cap 16 which 75 closes the outer end of the hub. The outer end of the inner member is made of such diameter as to permit the outer member to be passed freely thereover to apply said outer member to and remove it from the inner member. Said inner member is provided just outside of its tapered portion with 80 an exterior screw thread 17 adapted to receive an interiorly screw-threaded locking ring 18 which is arranged to engage the 85 outer member in a manner to force the tapered or cone-like portions of said members in wedging engagement when said locking ring 18 is turned inwardly toward the outer member. The spoke flange 13 is removably 90 fitted to the outer hub member, as before stated, and is formed at its inner margin with an annular flange 20 which engages over the outer surface of the outer hub member, and is provided outside of said flange 95 20 with an annular, radial flange 21 which extends inwardly toward the inner hub member. The said flange 21 terminates short of the inner hub member and is spaced a distance from the outer end of the outer hub 100 member so as to provide an annular chamber or recess 22 to receive the locking ring 18. The locking ring is formed with an annular outwardly extending flange 24 which extends outwardly through the space between the 105 flange 21 and the inner member, and terminates substantially flush with the outer face of the flange 21. The outer end of said locking ring flange 24 is fashioned to engage a suitable tool, as a wrench, by which the 110

locking ring may be turned inwardly against the outer member to force the tapered portions of said members into wedging engagement, and turned outwardly to draw the outer hub member away from the inner member. Such tool engaging portion of the end of the ring may be formed with spanner holes or may be made of polygonal cross section for engagement by a jaw wrench. As herein shown the end face of said locking ring flange 24 is formed with two diametrically opposed pairs of lugs 25, 25, the lugs of each pair being spaced a distance apart to provide notches 26 to receive the engaging parts of a wrench or like tool. The said notches, as herein shown, are undercut, (Fig. 6) and the inner walls of the notches are also disposed radially with respect to the axis of the hub. The angular formation of the inner or engaging walls of the lugs enables the same to be reliably engaged by a suitably shaped wrench or implement so as to prevent the implement from slipping off the locking ring when the latter is engaged with the ring to turn the same on or off. A convenient form of wrench may consist of a ring made of a diameter to pass over the outer end of the hub and provided with oppositely located lugs of a shape to engage and fit the notches 26 of the locking ring, one or both of said lugs being adapted to be moved outwardly, in any suitable manner, when the ring is being placed over the hub, and to be thereafter moved inwardly into the outer ends of the notches 26 and locked in engagement therewith. The suggested wrench may be provided with oppositely extending handles, movable relatively to said ring, and the lugs which are movable to engage the notches may be formed on said handles. In assembling the hub and locking ring thus described, the outer spoke flange 13 is first removed, at a time when the hub members are demounted, the locking ring placed up against the outer end of the outer hub member, and thereafter the flange 13 fitted and bolted to place. When the parts are thus assembled the locking ring is free to rotate relatively to the outer hub member but is confined from lateral separation with respect to said hub member and the flange. The swiveling connection of the locking ring with the hub member gives to said ring a pulling function, when turned backwardly, whereby the outer hub member is positively withdrawn from the inner member to demount the hub. By making the outer spoke flange 13 removable and recessing the flanges at their inner margins to receive the locking ring and to hold or confine said ring relatively in place, I provide an exceedingly simple, strong and efficient construction for mounting the combined locking and pulling ring, and a construction which enables the parts to be made and assembled at relatively

small cost. This construction also enables the locking ring to be housed and protected from injury, as by contact with external objects such as would tend to injure the screw-threaded connection of the locking ring or nut with the inner member. Furthermore the location of the locking ring or member shown, a distance inwardly from the end of the hub, serves to further protect the locking ring from injury. As a means of preventing the assembled hub members from rotating relatively to each other, in case the wedging engagement should fail by reason of the parts not being tightened together, I have shown an interlocking connection between the inner ends of the inner and outer hub members. As herein shown said tapered inner member 10 is provided at its inner end face with a plurality of angularly spaced, radial, lugs 28 separated by notches 29, (Fig. 4) and the inner end face of the outer hub member is provided, inwardly of the spoke flange 12, with a plurality of similarly spaced lugs 30 and intervening notches 31 (Fig. 3); the arrangement being such that when the hub members are assembled the lugs and notches of said members are interlocked to prevent one member turning with respect to the other. Said lugs may be cast on the hub members and machined to provide the proper interlocking engagement thereof, or the inner hub member may be originally formed with a solid radial flange, (indicated by the dotted lines at the notched portions of said member) and the outer hub member formed with a like solid inwardly extending flange and the notches 29 and 31 may be formed in said flanges by a suitable milling operation. The said lugs and the notches are preferably made of substantially equal lengths, and the lugs closely fit said notches to lock the assembled parts rigidly together. The interlocking connection produced by the lugs described prevents relative rotation of the hub members in case the wedging engagement of the tapered or cone-like surfaces thereof should fail, by reason of the fact that said tapers should not be forced sufficiently tight together. The hub shown in Figs. 7 and 8 is made like the hub before described, except as to variations required in applying the brake drum 35 thereto. As shown in Figs. 7 and 8 the inner hub member 10 is formed at its inner end with an integral, radially extending drum carrying flange 36, on the outer margin of which is formed or carried an integral, annular rim to constitute the brake drum 35. The outer hub member 11 may be provided with the lugs 30 such as are employed in the construction previously described, and said lugs are adapted to enter angularly spaced, arcuate openings 37 formed in said flange, the solid portions of the flange between said openings 37 consti- 120

tuting interlocking parts similar to the lugs 28 of the inner hub member of the construction first described. The said flange 36 is cast with the opening 37 therein, and the 5 walls of said openings may be finished, as by suitable drifting tools, to fit the same to the lugs 31 of the outer member. The nuts 38 of the bolts 39 by which the spokes are clamped between the spoke flanges are contained within openings 40 formed in the flange 36 to receive the same to permit said nuts to bear against the inner or integral spoke flange 12. The said openings 40 are made of such size that the nuts 38 will pass 10 freely into and out of said openings when the outer member is being applied to or withdrawn from the inner hub member. The remaining parts of the hub construction shown in Figs. 7 and 8 may be, and they are 15 shown as, made like the similar parts of the construction first described, and similar parts bear like reference characters.

In both of the forms shown the locking means are located exterior to the hub and at 25 a point where the interlocking elements may be readily and economically made and arranged to afford an exceedingly strong interlocking connection between the parts, and at a point where said lugs are exposed so as 30 to be readily observable in the event of breakage of the lugs. Moreover the arrangement of the lugs, as shown, on the rear end face of the outer member, permits the wedging or tapered engagement between the inner 35 and outer hub members to be carried entirely to the rear end face of the inner member, notwithstanding the presence of the interlocking lugs, and thereby materially increase the wedging engagement of said members, without lengthening the hub members. 40

The construction shown is capable of minor variations without departing from the spirit and scope of the invention, and I do not wish to be limited to the particular 45 construction and arrangement described, except as hereinafter specifically claimed.

I claim as my invention:—

1. A hub for a demountable wheel comprising an inner member, an outer member 50 removably fitted over the inner member and adapted to be separated endwise therefrom in demounting the wheel, said outer member comprising a main body portion and exterior front and rear spoke flanges, the front spoke 55 flange being removably fitted to the outer member, and the outer member terminating short of the plane of the front spoke flange, whereby there is provided within the plane of the base of the front spoke flange an out- 60 wardly opening annular recess, the rear wall

of which constitutes the front end of the outer member, and a locking ring occupying said recess and detachably fitted to the inner member and having swiveling engagement with said outer member and adapted to bear 65 against said shoulder.

2. A hub for a demountable wheel comprising an inner member, an outer member removably fitted over the inner member and adapted to be separated endwise therefrom 70 in demounting the wheel, said outer member comprising a main body portion and exterior front and rear spoke flanges, the front spoke flange being removably fitted to the outer member, and the outer member terminating 75 short of the plane of the front spoke flange, said front spoke flange being formed at its inner periphery with an annular flange which overlaps the front end of the said outer member, and with a radially directed 80 flange spaced at its inner periphery from the inner member to form a forwardly opening annular recess, and a locking ring screw-threaded to said inner member and extending through said recess, and provided with 85 in the plane of the front spoke flange with an annular flange adapted to fit within said recess behind the radial flange of said spoke flange.

3. A hub for a demountable wheel comprising an inner member, an outer member removably fitted over the inner member, said outer member comprising a main body portion and exterior front and rear spoke flanges, the front spoke flange being removably fitted to the outer member and adapted to be held in place by the means which clamp the wheel spokes between said spoke flanges, and the outer member terminating short of the plane of the front spoke flange, whereby 90 there is provided within the plane of the base of the front spoke flange an outwardly opening annular recess, the rear wall of which constitutes the front end of the outer member, and a locking ring occupying said 95 recess and detachably fitted to the inner member and having swiveling engagement with said outer member and adapted to bear against said shoulder, the front end of the locking ring having means for engagement 100 by a tool to turn the ring into and out of locking position.

In testimony, that I claim the foregoing as my invention I affix my signature in the presence of two witnesses, this 1st day of 115 December A. D. 1910.

THOMAS I. DUFFY.
